PYROMETER TUBE

James Ward Percy, Jersey City, N. J., assignor to
 United States Steel Corporation of Delaware, a
 corporation of Delaware

Application April 5, 1943, Serial No. 481,901

1 Claim. (Cl. 136—4)

This invention is concerned with the problem of determining the heating rate of a metal charge in a metal heating furnace. For example, the hot-rolling of steel slabs requires heating the slabs to a proper hot-rolling temperature, this involving the necessity for determining how long the slabs should remain in the furnace used to bring them to such a temperature, or, in other words, the heating rate of the slabs in the furnace.

The principles of the invention are illustrated by the accompanying drawing in which:

Figure 1 is a partial cross section of a continuous slab heating furnace with the invention in operation;

Figure 2 is an enlarged longitudinal section of a detail from Figure 1;

Figure 3 is an elevation of Figure 2;

Figure 4 is a side view of Figure 3; and

Figure 5 is a cross section from the line V—V in Figure 4.

More specifically, this drawing shows a partial cross section of a conventional continuous steel slab heating furnace 1 having a hearth 2 over which the slabs 3 are intermittently pushed transversely through the furnace, the furnace being provided with the usual series of observation ports 4 permitting observation of the slabs as they progress through the furnace. The various specific features involved are familiar to any one skilled in the art.

Heretofore, the customary way of determining the heating rate of the slabs as they progress through the furnace has been to measure the external surfaces of the slabs as they pass by the ports 4, the data obtained in this manner being used to regulate the temperature and time values of the slab heating cycle to assure the slabs reaching a proper hot-rolling temperature just prior to their leaving the furnace. Frequently, the furnace is provided with an automatic photocell radiation pyrometer with its cell 5 sighted through a tube 5^a on the slab surfaces at a position near the furnace slab exit, in order to determine that the slabs have in fact attained a hot-rolling temperature before they leave the furnace.

The outlined procedure involves the problem that it has been impossible to determine whether the slabs were heated throughout to the desired temperature, the heating rate of the slab surfaces being the only thing determined and this not providing an adequately safe guide to the internal heating rate of the slabs. That is to say, hot rolling requires the slabs to be heated

throughout to a proper hot-rolling temperature, yet the prior art has provided only for determining the heating rate of the external slab surfaces, this involving the necessity for calculating the internal slab temperatures instead of knowing them definitely.

According to the present invention, when it is desired to determine the heating rate of the slabs, a hole is drilled to the geometrical center of a representative one of the slabs as at 6. This hole is drilled from the side of the slab that passes opposite the ports 4 in such a manner that the hole attains axial alignment with these ports. As the slab passes successively by the various ports a thermocouple is slid in the hole 6 to the geometrical center of the slab and a temperature reading is obtained of the actual internal temperature of the slab, this involving conventional use of the thermocouple so far as obtaining the temperature value is concerned. In this fashion it is possible to obtain the heating rate at spaced time intervals of the actual inside of the slab at a point where the heat has the most difficulty of reaching. Preferably, the external heating rate is determined in the conventional fashion at the same times, the final result being complete knowledge of the actual heating rate of the slab both externally and internally as it progresses through the furnace. Obviously, any other furnace charge involving the same problem can be handled in the same fashion, and the principles involved may be applied regardless of whether the furnace is of the continuous type or the charge remains stationary in the furnace during its heating. It is only necessary to measure the internal temperature of the charge at spaced time intervals to provide the information discussed. The resulting information may be used, for example, to adjust the time and temperature values of the heating cycle, to test a new furnace design, or to indicate that an old furnace needs redesigning.

Preferably, special equipment should be used in carrying out this invention. With this in mind, the thermocouple is positioned in a quartz tube 7 having a closed end 8 and with its other end open to permit passage of the necessary leads to the thermocouple, these leads and the thermocouple not being illustrated because they may follow conventional design. Heat-resisting cement 9 fastens the tube 7 concentrically inside a larger tube 10 made of heat-resisting metal, such as 18—8 or 25—12 chromium-nickel stainless steel, and having a tapered end 11 extending beyond the closed end 8 of the quartz tube 7 so

as to protect this relatively fragile part, the end 11 of the tube 10 being tapered to permit its easier guidance into the hole in the slab. The arrangement is such that the outside of the tube 7 is spaced from the inside of the tube 10, in the interest of adequately protecting the tube 7 from damage, the tube 10 having side openings 10a exposing the tube 7 directly to the slab heat. The tube 10 is provided with a threaded end 12 opposite the end 11 and this threaded end is arranged in screw threaded engagement with a pipe 10b, also made of heat-resisting metal, which is of adequate length to project the tube 10 to the geometrical center of the slab by way of the hole in the latter from a position conveniently outside of the port 4 being used at the time.

A water-cooled tubular jacket 13 is provided with a vertically adjustable frame 14 carried by a wheeled carriage 15, this permitting the jacket 13 to be wheeled up to the port 4 and the jacket 13 then thrust through this port, the jacket 13 having a sufficiently large inside passageway to permit projection therethrough of the pipe 10 carried on the end of the pipe 10b, the end of the jacket 13 being positioned close to the side of the slab having the hole so that the pipe 10b is not directly exposed to the furnace heat. The jacket 13 is provided with a heat shield 16 for the comfort of the operator, and is pivoted to the frame 14, and provided with a counterpoise 17, whereby the operator may have some leeway in vertically aligning the jacket with the slab, other than by vertical adjustment of the frame 14. Furthermore, the passageway through the jacket

13 should be sufficiently large to permit some free lateral movement of the pipes 10 and 10b and, preferably, large enough to permit sighting therethrough, all to the end of enabling the operator to more conveniently and quickly thrust the tube 10 to the geometrical center of the slab 3 in a relatively short time, it being remembered that in a continuous furnace there may not be too much time to obtain a reading from the slab

10 at any one of the ports 4, and that it is necessary to get the thermocouple to the inside of the slab and withdraw it as quickly as is consistent with obtaining an accurate temperature measurement.

15 The quartz tube 7 is used to protect the thermocouple against the furnace atmosphere because it conducts heat with adequate rapidity. Actual use of equipment such as disclosed has shown that the disclosed protective features for 20 these parts are adequate to make its use completely practical.

I claim:

25 The combination of a quartz tube having a closed end for enclosing a heat radiation responsive device, a heat-resisting metal tube enclosing the quartz tube and having at least one side opening exposing the quartz tube, and heat-resisting cement mounting the quartz tube in the metal tube, the latter being of larger diameter than the former so as to provide a space between the two tubes, the end of the metal tube 30 extending beyond the closed end of the quartz tube.

JAMES WARD PERCY.
